(74) Attorney, Agent, or Firm—Dorsey & Whitney LLP

(57) **CLAIM**

I claim the ornamental design for the molded tray for beverage containers, as shown.

DESCRIPTION

FIG. 1 is a isometric view of the tray showing my new design.

FIG. 2 is a side-elevational view of the tray shown in FIG. 1.

FIG. 3 is a top plan view of the tray shown in FIG. 2; and, FIG. 4 is a bottom plan of the tray shown in FIG. 2.
